THEATER AISLE STANDARD

Henry J. McKinney, Brookline, Mass.

Application January 21, 1937, Serial No. 121,410

3 Claims. (Cl. 240—4)

At the end of each row of seats in a theater or similar building a special standard is used to give support to the seat next adjacent to the aisle. This element is commonly known as an aisle standard. In prior constructions provision has been made at times for illuminating a sufficient portion of the floor immediately adjacent to each standard to enable a person better to see the way to his seat. The present invention is more especially concerned with standards of this general type.

Considerations of appearance, design and ornamentation are very important in structures of this character, and much attention is given to them. It is therefore an object of this invention to devise an aisle standard in which the factor of illumination shall be made to contribute to the attractiveness and design of the standard. In addition, the invention aims to devise a construction of this character which will lend itself to great variation in design, while still retaining the manufacturing expense within entirely reasonable limits, and in which the illumination of the floor at the lateral entrances to the aisle will be performed more satisfactorily.

The nature of the invention will be readily understood from the following description when read in connection with the accompanying drawings, and the novel features will be particularly pointed out in the appended claims.

In the drawings,

Figure 1 is a perspective view of an end seat equipped with aisle standards embodying features of this invention;

Fig. 2 is a horizontal, sectional view approximately on the line 2—2, Fig. 1;

Figs. 3 and 4 are front and vertical sectional views, respectively, of the aisle standard shown in Figs. 1 and 2, the upper portion of the standard, however, being very slightly modified in appearance;

Figs. 5 and 6 are horizontal, sectional views of modifications; and

Figs. 7, 8 and 9 are views similar to Figs. 1, 2 and 4, respectively, showing a further modification.

Referring first to Figs. 1 to 4, inclusive, the aisle standard is indicated in general at 2. It comprises a casing designed to rest on the floor and equipped with the usual elements, such as the lugs 3—3, to receive parts which support the hinge members. In the aisle side of the standard a recess 4 is formed of considerable depth which forms a housing for an electric lamp 5. Preferably this lamp is of a tubular form, such

as that known commercially as the "Lumilite", although any other suitable form of lamp may be substituted for it. The particular lamp shown has terminals at its opposite ends designed to be supported in upper and lower sockets or fixtures 6 and 1, respectively. As shown in Fig. 2, the lower fixture is screwed to a lug 8 cast integral with the frame, and the upper fixture may be similarly mounted. The nature of this lamp supporting means necessarily will be varied to suit the requirements of the particular style of lamp used. However, because the lamp housing is vertically elongated and preferably occupies a considerable portion of the height of the standard, it is desirable to use a lamp of a tubular type. A further advantage of this type of lamp is that it gives a soft subdued light well suited to this particular use.

The back of the recess 4 is closed by the web portion 10 of the standard, this part forming a box-like structure which is open at the aisle side. Partially closing this side of the recess is a grill 12, usually made of metal, this closure being secured removably in place in any convenient manner. In the particular arrangement shown the upper edge of the grill is provided with lugs, one of which is shown in Fig. 4 at 13, designed to enter recesses in the casting and the lower edge is secured in place by screws or bolts 14—14, Fig. 1. As indicated in Figs. 2, 3 and 4, that part of the casting immediately surrounding the recess is grooved to receive the edge of the grill. Immediately behind the grill is a translucent plate 15 of any suitable material such as glass or, more preferably, some of the flexible translucent sheet materials now available, cellulose acetate being an important example.

It will readily be appreciated that an aisle standard constructed in the manner just described lends itself conveniently to a wide variety of ornamentation involving either features of configuration or color schemes, or both. Since the lamp housing is open at the aisle side for the passage of light into the aisle, the grill 12 appears in silhouette, and the design given to this member will be made accordingly. The translucent closure 15 serves both to keep dust out of the lamp chamber and also to tone down the volume of light, to modify its color, or to contribute in any of many ways to the entire design of the article. An almost endless variety of designs may be made in the same standard simply by changing one or both of the members 12 or 15, and without making any change whatever in the main portion of the standard. In addition,

this member may be made of relatively simple lines suited to take a wide variety in design, or, if desired, it may be of more ornamental form so that it contributes to the design. By suitable masking or coating of the translucent plate, as much or as little of it, as desired, may be made to transmit light, and to subdue or modify the characteristics of the rays. Also, the grill may be used without the translucent plate if desired.

10 The seat illustrated in Fig. 1 is shown as equipped with two end standards merely for the purpose of illustrating both the inner and outer sides of these members. In other words, the standard shown at 2 would be used at one end of a row of seats and that shown at 2' at the opposite end. The box portion 10' of the latter is shown as provided with openings 16 and 17 through which a small amount of light will be directed to the region under the seat, these openings also affording ventilation for the lamp chamber.

In some cases it is preferable to make the back of the lamp housing removable, and such a construction is shown in Fig. 5, the removable back being indicated at 18. One advantage of this construction is that the fixtures which support the lamp may be mounted directly on the removable back and these parts may be assembled as a unit prior to securing the back to the main body of the aisle standard. If the lamp is of a type in which the terminals are at one end only, then only the upper section of the back may be made removable, if desired, and this part may carry the lamp supporting devices. In some constructions, also, it is preferable to make the entire lamp housing and the parts immediately associated with it in a unit by itself, and to secure this unit removably to the standard. A construction of this nature is illustrated in Fig. 6, the lamp casing being shown at 20 positioned in an aperture or recess formed in the casting 2a for the standard and removably secured in position by bolts or screws 21-21. This casing may also carry the closures for the front side thereof.

45 In all of these forms of the invention the standard is provided with lugs 22-22 at its upper end to receive the wood arm rest 23.

A further variation of the invention is shown in Figs. 7, 8 and 9. Here the standard casting 25 is provided with a relatively deep, vertically elongated recess 26 and either all, or a portion, of the back 27 is removably secured in place by screws or bolts. Preferably this back is equipped with one or more brackets 28, as may be required, to support the lamp 30. The recess 26 in this standard also is open at the aisle side, but this opening is partially closed by a series of inclined elements 31 somewhat resembling louvers which may either be cast integral with the part 25 or removably assembled therewith as desired. The inclined portion of each louver preferably is substantially overlapped by the marginal flange or skirt at the outer and lower edge of the corre-

sponding member next above it, so that direct horizontal rays of light cannot be transmitted laterally from the lamp into the aisle, but downwardly directed diagonal rays will be permitted to pass between the louvers and thus to illuminate the portion of the floor immediately adjacent to the standard. In this construction the marginal edges of the members 31 produce a grill-like effect, and these parts, as well as the body portions of the members 31, may be given ornamental shapes and attractively decorated. Thus the ornamental effects desired may be produced, while at the same time affording the necessary control of light.

If desired, the grill 12, Fig. 1, may be replaced by a louver assembly like that shown in Figs. 7, 8 and 9, such an assembly being slipped into place in the same manner as the grill and a translucent plate may be used with the louvers or not.

While I have herein shown and described typical embodiments of my invention, it will be understood that the invention may be embodied in other forms without departing from the spirit or scope thereof.

Having thus described my invention, what I desire to claim as new is:

1. An aisle standard for theater seats provided with a lamp housing in the side thereof toward the aisle, said housing opening at the aisle side, a light transmitting closure for the open side of said housing comprising and including a grill extending substantially the full length of the standard, an electric lamp mounted in said housing in a position to throw its rays outward through the grill and into the aisle, and a translucent member covering the open portions of the grill.

2. An aisle standard for theater seats provided with a lamp housing in the side thereof toward the aisle, said housing opening at the aisle side, a light transmitting closure for the open side of said housing comprising and including a grill extending substantially the full length of the standard, an elongated electric lamp mounted in said housing in position to throw its rays outward through the grill and into the aisle, and a translucent member covering the open portions of the grill.

3. An aisle standard for theater seats provided with a lamp housing in the side thereof toward the aisle, said housing extending the greater part of the height of the standard and being open at the aisle side thereof, a tubular electric lamp mounted in said housing, a light transmitting closure for the open side of said housing comprising and including a partially translucent grill extending substantially the full length of the standard, upper and lower fixtures supporting said lamp, and a supporting member for said fixtures and the lamp removably mounted in said recess, whereby said fixtures, lamp and member are removable and replaceable as a unit.

HENRY J. MCKINNEY.
